UNITED STATES PATENT OFFICE.

JOHN V. CUNNIFF, OF FALL RIVER, MASSACHUSETTS, ASSIGNOR TO DRAPER COMPANY, OF HOPEDALE, MASSACHUSETTS, A CORPORATION OF MAINE.

ROTATABLE SPINDLE.

No. 920,830.

Specification of Letters Patent.

Patented May 4, 1909.

Application filed November 20, 1908. Serial No. 463,685.

To all whom it may concern:

Be it known that I, JOHN V. CUNNIFF, a citizen of the United States, and resident of Fall River, county of Bristol, State of Massachusetts, have invented an Improvement in 5 Rotatable Spindles, of which the following description, in connection with the accompanying drawing, is a specification, like characters on the drawing representing like 10 parts.

This invention relates to rotatable spindles for spinning and twisting yarn, and it has for its object the production of means to center automatically and maintain the spindle in proper upright position, whereby vibrational movements of the spindle due to an unbalanced load will be prevented and the spinning or twisting operation improved. 15

The drawing shows in side elevation and 20 partial section a sufficient portion of a rotatable spindle and its bearing, with one embodiment of my invention applied thereto.

The spindle 1 having an attached sleeve-whirl 2, and the depending rigid pintle 3 of 25 the spindle, may be of substantially well known construction, except that I have shown the spindle as annularly shouldered at 4, and the extremity of the pintle is screw-threaded at 5, see dotted lines, for purposes 30 to be described.

The bolster-case 6, adapted to pass through the spindle-rail R, is adapted to contain a lateral bearing or bolster 7, of any suitable character and forming no part of my present 35 invention, but herein I have shown the lower end of the case 6 as open, to receive therein with a tight or driving fit a short sleeve 8. This sleeve has fixedly secured to it the lower end of a tubular spindle-step 9, 40 extended upward within the casing, the annular shoulder 4 of the spindle seating upon the upper end of the step, to vertically support the spindle.

The spindle pintle 3 passes freely through 45 the tubular step and projects beyond its lower end, as shown, and upon the threaded part 5 is screwed a steadyng member, herein shown as a circular plate 10, made of metal, and secured in place by a check-nut 11.

50 A slight clearance is provided between the step 9 and the pintle 3 in order that the latter can move freely laterally for a limited distance, this freedom of movement being provided to enable the spindle when running at speed to find its true center of rotation.

This centering, however, is greatly assisted and the spindle more rapidly and accurately centered when running under an unbalanced load by means of the steadyng member 10, which by its weight and its location at the 5 lower end of the spindle always tends to maintain the proper centralization of the spindle.

The oil in the case 6 will collect between the step 9 and the wall of the case, and is prevented from leaking at the bottom of the latter by the tight fit between the case and the sleeve 8, and between the latter and the step.

So far as the invention is concerned the 70 step and sleeve may be made separate and fitted together or they may be made integral one with the other.

The size of the steadyng member, and its weight, may be varied according to circumstances, to properly coöperate with the spindle and perform the desired functions, such variations depending upon the spindle speed, load, etc.

When it is desired to remove the spindle or 80 to change the lateral bearing or bolster the steadyng member can be readily detached and the spindle can then be withdrawn from the case.

Having fully described my invention, what 85 I claim as new and desire to secure by Letters Patent is:—

1. A bolster-case open at its lower end, a bolster located in the bolster-case, and a rotatable spindle laterally supported by the 90 bolster, combined with a tubular, vertical support for and through which the depending end of the spindle freely extends, said support being fixedly held in the lower end of the bolster-case, and a steadyng member 95 fast on the depending end of the spindle outside the bolster-case.

2. The combination, with a bolster, a bolster-case, and a vertical spindle-support therein, of a rotatable spindle sustained by 100 the bolster and said support and having its lower end projecting below the bolster-case, and a circular steadyng member fast on the projecting end of the spindle and independent of the spindle-supporting means.

3. The combination, with a bolster, a bolster-case therefor open at its lower end, and a tubular spindle-step fixedly held in the open end of the bolster-case, of a rotatable 110 spindle extended through the bolster and

- step and projecting below the bolster-case, a steadyng member fast on the projecting end of the spindle, and a shoulder on the latter to seat upon the upper end of the spindle-
5 step, the depending end of the spindle being free to move laterally in the step as the spindle centers itself.
4. The combination, with a case open at its lower end, a tubular spindle step fixed
10 therein, and a lateral bearing for the spindle within the case, of a rotatable spindle having its depending pintle extended freely through and projecting beyond the step, a steadyng member fast on the pintle below the bottom
15 of the case, and an annular shoulder on the spindle to rest upon the top of the step.
5. The combination with a rotatable spindle, of means to support the same laterally and vertically, and a steadyng member fast

on the rigid portion of the spindle below its 20 lateral support, to properly center the spindle and minimize vibrational movement thereof.

6. The combination with a rotatable spindle, a case, and means within the case to 25 laterally and vertically support the spindle, the rigid pintle of the latter extending downward below such supporting means, of a steadyng member mounted on the lower end of the pintle.

In testimony whereof, I have signed my name to this specification, in the presence of two subscribing witnesses.

JOHN V. CUNNIFF.
